CALCULATING MACHINE

Ernest Racz, Detroit, Mich., assignor to Burroughs
Adding Machine Company, Detroit, Mich., a
corporation of Michigan

Application April 8, 1933, Serial No. 665,057

17 Claims. (Cl. 197—128)

This invention relates to a calculating machine. It is directed particularly to the paper handling equipment of such a machine although it also concerns a combination by means of which a record of transactions may be kept and a receipt issued for handing to a customer.

In many lines of business it is desirable to have a machine that will accumulate the transactions that occur from time to time, will record them on a record sheet that is inaccessible to the operator, and that will print each of the items on an independent work sheet or ticket of which all or a portion may be handed to the customer as his receipt. It is highly desirable that the work sheet or ticket be easy to insert and remove. This ticket should, in many cases, be moved a different distance than the record sheet so as to space the printed matter on it at different distances than the matter appearing on the record sheet. It is important that the ticket be moved accurately to its different printing positions and held while the printing operation takes place, but this should be done without interfering with the ready insertion or removal of the ticket. The present invention is directed to a solution of this problem.

The general object of the invention is to provide an improved paper handling equipment for a machine of the class described.

A more particular object is to provide an improved machine that will make a record of each transaction and, at the same time, will print on a work sheet or ticket that may be readily removed after the printing operation takes place and another ticket inserted.

Another object is to provide a mechanism of this kind that will grip and hold the ticket so that it will be accurately moved to the proper printing position and held there while the printing operation takes place.

Still another object is to provide a machine of this character that will enable the work sheet or ticket to be spaced differently than the record sheet and independently thereof.

Other objects and advantages of the invention will appear from the following specification and drawings.

An embodiment of the invention is shown in the accompanying drawings in which:

Figure 1 is a perspective view of a portion of a calculating machine with the invention applied thereto, all parts being in normal position and a ticket or work sheet inserted in position prior to operation of the machine;

Fig. 2 is a partial section and side elevation en-

larged to show the means for holding and spacing the ticket;

Fig. 3 is a partial right side elevation and section showing particularly the ticket lifting means, the ticket being shown lifted to a position to receive a second printing impression;

Fig. 4 is a partial left side elevation showing certain of the controls;

Fig. 5 is a partial right side elevation showing certain other controls; and

Fig. 6 illustrates a ticket and a record sheet spread apart to show the relation of the entries on each.

The invention is shown associated with a Burroughs portable calculating machine of the type illustrated and described in Horton Patent No. 1,853,050. Portions of this machine have been illustrated in the present drawings and a brief description of some of the calculating machine features will be given here but reference is made to the above patent for details.

The machine is of the type that is given a forward and a return stroke of operation by hand or by a motor, the machine illustrated being motor driven. The machine has a plurality of banks of depressible amount keys 10, and is provided with latch plates 11 for latching and locking the keys under certain conditions. The depressed amount keys control the movements of actuator racks 12 that are released during operations of the machine. At the time that the actuator racks are differentially positioned in accordance with the amount keys depressed, or in accordance with the amount in the register when a total is taken, suitable type bars 13 are also differentially positioned and, during the latter part of the forward stroke of the machine, a printing mechanism, including the hammers 14, is operated to drive the type bars rearward against the platen 15.

The machine has a main drive shaft 16 (Fig. 3) which is given a forward and a return stroke of movement during each machine operation, the forward stroke of the shaft being in a counter-clockwise direction as viewed in Fig. 3 and the return stroke being in a clockwise direction. In the embodiment illustrated, the shaft 16 is driven by a motor, not shown, but the controls for which are illustrated in Fig. 3. These controls include an arm 17 pivoted loosely on a shaft 18 and 50 yieldingly connected by a spring 19 to a second arm 20 rigidly fixed to the shaft 18. When the arm 17 is rocked clockwise, as viewed in Fig. 3, its motion is transmitted through the spring 19 and the arm 20 to the shaft 18 which is thus 55

rocked clockwise. The rocking of this shaft clockwise causes the motor to give the machine a stroke of operation.

The platen 15 is line spaced during each return 5 stroke of operation of the machine by mechanism indicated generally at 21 in Fig. 3.

The machine has one or more registers 22 for receiving items and from which totals may be taken.

10 The machine is also provided with total taking mechanism controlled by the keys T and ST; with a non-add mechanism; and with other calculating machine features such as disclosed in the patent above mentioned.

15 *Record sheet control*

In the embodiment illustrated a record sheet 23 is passed underneath the platen from the rear and around the same so that the sheet will receive 20 impressions from the printing mechanism. The record strip is held in feeding engagement with the platen 15 by feed rolls 24 so that the sheet is fed forward as the platen is line spaced. The upper end of the record strip passes into a lockable compartment 25 (Fig. 1) access to which is controlled by a detachable key operating in the lock 26 so that only an authorized person may remove the record sheet from the machine.

30 *Work sheet receiving and supporting means*

The ticket or work sheet is dropped into position by hand in front of the platen and, in this respect, the machine may be said to be a front-feed machine.

35 For receiving the work sheet 30 there is provided a paper chute 31 which is preferably made of one piece of metal bent to the shape illustrated in Figs. 1 and 2. This chute comprises a back portion 32 and two spaced front portions 33 and 34. The front portions have forwardly extending arms 35 and 36 by means of which the chute is supported on pins 37 on the plate that supports the ribbon mechanism. The spacing of the front parts 33 and 34 of the chute provides 40 an opening between them for the type bars 13.

45 The chute 31 is positioned between two webs 40 and 41 of an ink ribbon which pass along the printing line of the platen. This places one ribbon web 40 in front of the paper chute and the other web 41 to the rear of the chute. When 50 the type bars 13 are driven to printing position they strike the front ribbon and make an impression on the portion of the work sheet immediately to the rear. The rear ribbon web 41 makes 55 a duplicate impression on the record work sheet 23 on the platen. The ribbon is preferably wound from one reel 42 over suitable guide posts 43, 44, 45 and 46 back to another reel 47 on the same side of the machine, suitable ribbon feeding mechanism and automatic ribbon reverse being provided, neither of which has been shown 60 in this application, but suitable types of which are disclosed in the patent referred to.

65 *No. 1 operation*

The first operation of the machine resembles a normal operation of a calculating machine with variations as will now appear.

70 It is assumed that a record strip 23 is about the platen and that a ticket has been inserted in the chute.

The operator first depresses the keys that control the printing of the date, these usually being the three left hand banks of keys on the machine.

75 He then depresses an operation key 50 which, for

purposes of convenience, will be called the "No. 1 operation key". The stem of key 50 is positioned over a projection 51 on an arm 52 pivoted on a stud 53. The free end of arm 52 is positioned over a stud 54 on a motor control plate 55 which is slidably mounted on a frame stud 56 and the shaft 18, and is urged upward by a spring 51. The motor control plate 55 has a rearwardly extending arm 58 positioned over a stud 59 on the arm 17 that controls the motor drive.

When the No. 1 operation key 50 is depressed the control plate 55 is moved down which rocks the arm 17 clockwise, as viewed in Fig. 3, to cause the motor to give the machine a stroke of operation.

10 Since the operator may wish to make many entries on the same date it should not be necessary for him to depress the date keys for each entry. Accordingly, provision has been made for locking the date keys depressed and, instead of making 20 these keys releasable by means of the error key, as is usually the case, the keys can be released only by depression of the total key.

15 Referring to Fig. 4, each bank of keys in a regular machine is provided with a latch plate 61 urged forward, or to the left in Fig. 4, by a spring 61. When one of the keys is depressed, the latch plate is cammed rearwardly against the tension of the spring 61 after which the plate moves forward and a nose 62 on the plate latches the depressed key in depressed position. The keys are then normally released as follows:

20 Attached to the main drive shaft 16 is a cam plate 128 carrying a stud 64 that normally engages the end of a member 65 slidably and rockably 25 mounted on a frame stud 66, the member being urged clockwise about its pivot by a spring 67, but normally held against such movement by the stud 64. The forward end of the member 65 has a cam surface 68 adapted to cooperate with a control rod 69 extending across the front of the machine and suspended by arms, not shown, from a shaft 70. Pivoted on the shaft 70 at the front of the machine are a plurality of members 71 which are connected by lugs 72 to the latch plates 61, 30 there being a member 71 for each bank of keys. Normally the lower ends of the members 71 straddle the control shaft 69 as illustrated and described in the Horton patent referred to.

35 The normal position of the parts is illustrated 35 in Fig. 4. During the forward stroke of the machine the stud 64 moves away from member 65 which is thereupon pulled rearwardly and upwardly by the spring 67. During the return stroke of the machine the stud 64 again engages the member 65 and, at that time, the cam surface 68 is immediately to the rear of the control rod 69. The result is that the control rod is moved 40 clockwise about its pivot 70 and the upper ends of the arms 71 are moved to the rear to move the latch plates rearwardly to release the depressed 45 keys.

45 In the present case only the members 71 for the banks of date keys are illustrated and these members do not straddle the control shaft 69. Instead these members are cut away, as illustrated in Fig. 5, at 73. These members have rearwardly projecting arms 74 acting as zero stops for the index bars 75 of the machine. The urge of springs 61 on latch plates 61 tends to swing the 50 members 71 clockwise in Fig. 5 but means is provided to prevent this comprising a bail 76 pivoted on shaft 70 and urged by a spring 77 against a limit bar 78.

55 By referring to Fig. 5, it will be clear that when 75

the shaft 69 is rocked forward or counterclockwise, as viewed in Fig. 5, the members 11 for the banks of date keys will not be rocked counterclockwise and the date keys will not be released, 5 nor will the zero stops 74 move to position to arrest the index bars 75.

Positioned under the stem of the total key T (Fig. 4) is one arm 80 of a bell crank lever pivoted at 81. This bell crank lever has another 10 arm 82 on which is pivoted a pawl 83 urged counterclockwise, as viewed in Fig. 4, by a spring 84. The forward end of this pawl has a shoulder 85 positioned over a lateral lug 86 on an arm of yoke 87 pivoted on the shaft 70. This yoke extends 15 across the machine and is provided with upstanding lugs 88 in front of the banks of date keys.

When the total key T is depressed, the bell crank 80—82 is rocked clockwise (Fig. 4) which moves the pawl 83 forward until it is engaged by a stud 89. This rocks the yoke 87 clockwise, as 20 viewed in Fig. 4, and pushes the latch plates 11 of the banks of date keys to the rear to release these keys. The latch plates 11 are yieldingly connected by springs 90 to the zero stops 74 so 25 that these are pulled to index-bar-releasing position if not already in that position.

In this manner the date keys are automatically released when a total is taken and they cannot be released in any other way.

30 The machine is provided with a suitable printing control mechanism, portions of which are shown in Fig. 3, so that certain sections of the printing mechanism can be disabled. The No. 1 operation key controls this mechanism so 35 that, even though some of the amount keys in the columns used for printing items are depressed, nevertheless, no printing will occur in these columns. In the embodiment of the invention illustrated, only the date, controlled by the three left hand banks, and a folio number, controlled by 40 the next five banks, may be printed when the No. 1 operation key is depressed.

Depression of the No. 1 operation key also non-adds the machine so that nothing enters the register during the No. 1 machine operation. This 45 non-add mechanism has not been shown but is disclosed in detail in the patent heretofore mentioned.

Work sheet moving means

50 The work sheet or ticket is moved upwardly in the paper chute and, as previously mentioned, this movement is independent of the platen.

Positioned near the lower part of the paper 55 chute are two ticket lifting pawls 100 and 101 (Fig. 1) which are spaced apart so as to lift each side of the ticket. These pawls are pivoted on the ends of arms 102 and 103 respectively of a yoke 104 pivoted on a shaft 105.

60 The lifting pawls have shoulders 106 and 107 respectively which are adapted to engage the under side of the ticket to lift it. Normally these shoulders are forward in an inactive position, as shown in Fig. 1, but the pawls are provided with cam surfaces 108 (Fig. 2) which, when the pawls are raised, engage the edge of the slots 109 through which the pawls move, and this causes the pawls to swing rearwardly so that the shoulders move under the bottom edge of the ticket for lifting the same.

70 One of the improved features of the machine is that the ticket is not only lifted but it is held while it is lifted and while printing occurs so that the ticket will not be thrown beyond the proper position but will be accurately moved to and held

in the correct position. This result is accomplished by a very simple construction as follows:

Each of the lifting pawls is provided with an upward extension having a rounded head 110, as 5 illustrated in Fig. 3. The shape of the cam edge 108 of the pawls is such that they are cammed rearward far enough to cause this rounded head 110 to press the ticket into engagement with the rear portion 32 of the paper chute, the pressure 10 being sufficient to firmly hold the ticket in position without interfering with its upward movement. The ticket is thus gripped at the same time that the shoulders of the lifting pawls are moved under the bottom edge of the ticket, then, 15 as the lifting pawls move upward, the shoulders push up on the ticket and the rounded heads hold the ticket so it will not jump or bound away when the pawls are stopped.

It is desirable to release the ticket after a printing operation so that it may be readily removed, and this is accomplished very simply by providing the rear edges of the lifting pawls with cam surfaces 111 (Fig. 2) adapted to engage adjustable abutments 112 which positively cam 25 the pawls forward as they are lowered to normal position. This insures that the ticket will be released.

During the No. 1 operation of the machine the lifting pawls are not raised, for reasons that will 30 presently appear, but, during the No. 2 operation, the pawls are raised and they space the ticket a considerably greater distance than the normal line space movement of the platen, as shown in Fig. 5. It will be observed also that the ticket 35 is not in feeding contact with the platen. It is raised independently of the platen, that is, it does not depend upon frictional engagement with the platen to be line spaced.

The yoke 104 whose arms carry the lifting pawls 40 are yieldingly connected by a spring 113 to another yoke 114 having two arms 115 and 116. The arm 116 normally engages the stud 139 on arm 140, as shown in Fig. 1. The arm 115 has a forked end comprising a lower branch 117 and an upper branch 118. The upper branch carries a passby pawl 119 urged clockwise, as viewed in Fig. 1, by a spring 120, the pawl being limited in its clockwise movement by the engagement of a lateral lug 121 on the pawl with the edge of branch 118 50 of the arm 115.

The forked end of the arm 115, including the pivoted passby pawl 119, is adapted to straddle a flattened stud 122 which is rocked during each machine operation. This stud is carried on an 55 arm 123 (Fig. 3) of a yoke 124 pivoted at 125. This yoke has another arm 126 connected by a link 127 to the main driving cam 128 on the drive shaft 16. Each time the machine is given a stroke of operation the main driving cam 128 is moved counterclockwise to its Fig. 3 position and then returned clockwise to normal. During this movement the stud 122 is first raised from its Fig. 1 to its Fig. 3 position, then returned to its 60 Fig. 1 position.

When the yoke 114 is in normal position, shown in Fig. 1, the passby pawl 119 is out of the path of the stud 122 and, when the stud is moved upwardly during a machine operation it does not engage the passby pawl and the operation is an 65 idle one as far as rocking the yoke 114 is concerned. But, when the No. 2 operation of the machine is effected these parts are conditioned for operation, as will presently appear.

No. 2 operation

During the second operation of the machine the ticket is spaced and controlled as follows:

5 Prior to the second operation, the operator depresses the amount keys corresponding to the amount of the item that is to be entered in the machine. The date keys remain depressed but do not print the date during the machine operation as will later appear.

10 After the amount keys have been depressed, the No. 2 operation key 130 is depressed, which conditions certain parts of the machine and causes an operation as follows:

15 The stem of the key 130 is positioned over a lateral lug 131 on a portion of the motor control slide 55 so that depression of the key 130 moves the slide downwardly to rock the arm 17 clockwise to cause the motor to give the machine a stroke of operation.

20 The stem of the key 130 is also positioned over a lug 132 (Fig. 1) on a yoke 133 pivoted on the stud 53 (Fig. 3). This yoke has a rearwardly extending arm 134 provided with a stud 135 positioned over one end of a lever 136 pivoted at 137. The other end of this lever has an upwardly extending cam end 138 positioned to cooperate with a stud 139 on an arm 140 pivoted at 141 to a side plate of the machine and urged clockwise, as viewed in Figs. 1 and 3, by a spring 142.

25 When the key 130 is depressed the lever 136 is rocked counterclockwise. This moves the stud 139 upward slightly and the latter rocks the yoke 144 clockwise, as viewed in Fig. 1. This moves the forked end 117—118 of arm 115 upward and forward so that this forked end now straddles the stud 122. Accordingly, when the stud 122 is rocked upwardly, as it is during the machine operation that is initiated by depression of a key 130, the stud 122 engages the passby pawl 119 and rocks the yokes 114 and 104 clockwise to raise the lifting pawls 100 and 101 which operate as heretofore described.

30 During the return stroke of operation of the machine, the stud 122 is moved downwardly again. During this downward movement the stud engages the lower part 117 of the forked end of arm 115 and forcibly rocks the yoke 144 counterclockwise to normal. The yoke 104 has a lug 150 (Fig. 1) positioned behind the edge of the arm 115 so that, as the arm 115 is returned to normal, the yoke 104 will be forcibly returned to normal. In this manner the lifting pawls are returned positively to normal and they are positively released by the action of the cams 111, heretofore described.

35 The No. 2 operation key 130 does not non-add the machine when it is depressed, hence the item entered on the amount keys will be added in the register during the No. 2 operation of the machine.

40 The No. 2 operation key conditions mechanism that blocks printing in the date section of the machine and the date will not be printed during the No. 2 operation even though the date keys are depressed.

45 It will thus be seen that, when the No. 2 operation key is depressed, an operation of the machine is initiated and the parts are conditioned so that the printing in the date section is blocked, the work sheet is automatically gripped and raised to a new position where it is held, the platen is line spaced, and the parts are subsequently returned to normal, the work sheet gripping means being positively released.

50 At the end of the No. 2 operation the tension of spring 142 returns the lever 140 clockwise and the stud 139 returns lever 136 to normal.

5 It is to be understood that the construction shown is for purposes of illustration only and that variations may be made in it without departing from the spirit and scope of the invention as defined by the appended claims.

I claim:

1. A front-feed machine of the class described, 10 having a platen, means for holding a record sheet about said platen in feeding relation thereto, front-feed means for receiving and loosely supporting a work sheet in printing position in front of said platen but out of feeding contact therewith, means operating automatically during a machine operation to line space said platen and means operating automatically during the same machine operation to grip said front-fed work sheet and move the same to a 15 different printing position.

2. A front-feed machine of the class described having a printing mechanism, a platen, means for holding a record sheet about said platen in feeding relation thereto, front-feed means for receiving and loosely supporting a work sheet in substantially vertical position in front of said platen but out of feeding contact therewith, means acting automatically during a machine operation to line space said platen, means operating automatically during the same machine operation to grip said work sheet and raise the same vertically a considerably greater distance than the line space movement of the platen, and means automatically releasing said work sheet 30 after a printing operation has taken place.

3. A front-feed machine of the class described having a printing mechanism, a platen, means for holding a record sheet about said platen in feeding relation thereto, a vertical paper chute 40 positioned in front of said platen to receive and loosely support a work sheet in printing position in front of said platen but out of feeding contact therewith, said paper chute having a back plate, and means operating automatically 45 during a machine operation to releasably press said work sheet into contact with said back plate and to raise said sheet to a new printing position while it is so held, said last named means automatically releasing said work sheet after a 50 printing operation has taken place.

4. A front-feed machine of the class described having a platen, means for holding a record sheet about said platen in feeding relation thereto, front-feed means for receiving and holding a 55 work sheet in substantially vertical printing position in front of said platen but out of feeding contact therewith, means operating automatically to line space said platen during a machine operation, and means operating automatically 60 during the same machine operation to raise said work sheet independently of movement of the platen to line space the same said latter means including means to prevent over-movement of said work sheet when being line spaced.

65 5. A front-faced machine of the class described having a platen, means for holding a record sheet about said platen in feeding relation thereto, front-feed means for receiving and loosely supporting a work sheet in printing position in front of said platen but out of feeding contact therewith, means operating automatically 70 during a machine operation to line space said platen, and means operating automatically during the same machine operation to grip the 75 work sheet when being line spaced.

work sheet and move it, while it is gripped, in the same direction as the platen but for a considerably different distance, and means operating to release said work sheet during the latter part of said machine operation.

5 6. A machine of the class described having a printing mechanism, a platen means for holding a record sheet about said platen means for receiving a work sheet and loosely supporting the same in printing position relative to said platen but out of feeding contact therewith means for line spacing said record sheet during a machine operation, means including sheet-engaging members acting automatically during a machine 10 operation to line space said work sheet independently of the platen, and cam means causing said members to grip said work sheet while it is being line spaced.

10 7. A machine of the class described having a printing mechanism, a platen, a vertical paper chute adapted to receive and loosely support a work sheet in substantially vertical printing position relative to said platen but out of feeding contact therewith, lifting members engaging an edge of said sheet, means acting automatically during a machine operation to raise said members to line space said sheet, and cam means causing said members to also grip said sheet while it is being raised.

15 8. A machine of the class described having a printing mechanism, a platen, a vertical paper chute adapted to loosely receive and loosely support a work sheet in substantially vertical printing position, said paper chute having a back plate, lifting members for engaging said work sheet to raise the same, means acting automatically during an operation of the machine to raise said members to lift said work sheet, and cam means causing said members to releasably press said work sheet against said back plate while said work sheet is being raised.

20 9. A machine of the class described having a printing mechanism, a platen, a vertical paper chute adapted to receive and loosely support a work sheet in substantially vertical printing position, lifting members adapted to engage an edge of said sheet, said members being normally out of effective position, means operating automatically during a machine operation to raise said members to lift said sheet, and cam means automatically moving said members to effective position as they are raised, said cam means also causing said members to grip said sheet to hold it while it is being line spaced.

25 10. A machine of the class described having a printing mechanism, a platen, means for receiving a work sheet and loosely supporting the same in printing position relative to said platen but out of feeding contact therewith, means including sheet-engaging members engaging the lower edge of said sheet and acting automatically during a machine operation to line space said work sheet independently of said platen, cam means causing said members to also grip said work sheet while it is being line spaced, and cam means causing said members to release said work sheet during the latter part of the machine operation.

30 11. A machine of the class described having a printing mechanism, a platen, a vertical paper chute adapted to receive and loosely support a work sheet in substantially vertical printing position, said paper chute having a back plate, lifting members for engaging said work sheet to raise it, means acting automatically during an

operation of the machine to raise said members to lift said work sheet, cam means causing said members to releasably press said work sheet against said back plate while said work sheet is being raised to prevent over-movement of the work sheet, and cam means acting on said members to move them to paper releasing position during the latter part of the machine operation that raises said work sheet.

35 12. A machine of the class described having a keyboard, a printing mechanism, a platen, means for receiving and loosely supporting a work sheet in substantially vertical printing position relative to said platen but out of feeding contact therewith, means engaging an edge of said work sheet and gripping said work sheet to move the same, normally inactive means for raising said engaging and gripping means, and connections controlled by a manipulative member on the keyboard for placing said raising means in effective condition and to cause it to operate automatically during a machine operation to raise said gripping means to cause the latter to grip said work sheet and move it to and hold it in a new printing position and means automatically releasing said gripping means during the latter part of the machine operation.

40 13. A machine of the class described having a printing mechanism, a platen, means for holding a record sheet about said platen in feeding relation thereto, means for receiving a work sheet and loosely supporting the same in printing position relative to said platen so that a printing impression may be made on said sheet, but out of feeding contact therewith, means other than said platen operating automatically as the machine is operated to grip said work sheet and move the same within said holding means to line space the work sheet to a second printing position relative to said platen, and means automatically releasing said gripping means to free said work sheet after a printing operation has occurred so that said sheet is loosely supported in said holding means free for removal until the next machine operation.

45 14. A machine of the class described having a printing mechanism, a platen, means for holding a record sheet about said platen in feeding relation thereto, means for receiving a work sheet and loosely supporting the same in printing position relative to said platen so that a printing impression may be made on said sheet, but out of feeding contact therewith, means other than said platen engaging an edge of said work sheet and operating automatically as the machine is operated to grip and move the same within said holding means to line space the work sheet to a second printing position relative to said platen and to grip said work sheet to prevent over-movement thereof beyond said latter printing position, and means for automatically releasing said gripping means to free said work sheet after a printing operation has occurred so that said sheet is loosely supported in said holding means free for removal until the next machine operation.

50 15. A machine of the class described having a printing mechanism, a platen, means for holding a record sheet about said platen in feeding relation thereto, means for receiving a work sheet and loosely supporting the same in printing position relative to said platen so that a printing impression may be made on said sheet, but out of feeding contact therewith, means other than said platen engaging an edge of said work sheet and operating automatically as the machine is oper-

ated to move the same within said holding means to line space the work sheet to a second printing position relative to said platen, said means also engaging the surface of said work sheet to grip the latter to prevent over-movement thereof beyond said second printing position, and means for automatically releasing said gripping means to free said work sheet after a printing operation has occurred so that said sheet is loosely supported in said holding means free for removal until the next machine operation.

16. A machine of the class described having a printing mechanism, a platen, means for holding a record sheet about said platen in feeding relation thereto, a paper chute provided with a back portion, said chute being adapted to receive a work sheet and loosely supporting the same in printing position relative to said platen so that a printing impression may be made on said sheet, but out of feeding contact therewith, means other than said platen operating automatically as the machine is operated to releasably grip said work sheet against said back portion and to move the same within said holding means to line space the work sheet to a second printing position relative to said platen while it is so held, and means auto-

matically releasing said gripping means to free said work sheet during the latter portion of the machine operation, so that said sheet is loosely supported in said holding means free for removal until the next machine operation.

17. A machine of the class described having a printing mechanism, a platen, means for holding a record sheet about said platen in feeding relation thereto, a paper chute provided with a back portion, said chute being adapted to receive a work sheet and loosely support the same in printing position relative to said platen so that a printing impression may be made on said sheet, but out of feeding contact therewith, reciprocating lifting pawls operating automatically as the machine is operated to releasably grip said work sheet against said back portion and to move the same within said holding means to line space the work sheet to a second printing position relative to said platen while it is so held, and means automatically releasing said gripping means to free said work sheet during the latter portion of the machine operation so that said sheet is loosely supported in said holding means free for removal until the next machine operation.
